UNITED STATES PATENT OFFICE.

WILLIAM MORRISON AND JAMES E. NEAL, OF CLARKSVILLE, IOWA.

DESIGN FOR A BED-SLAT SUPPORT.

SPECIFICATION forming part of Design No. 30,401, dated March 28, 1899.

Application filed March 1, 1899. Serial No. 707,402. Term of patent 7 years.

To all whom it may concern:

Be it known that we, WILLIAM MORRISON and JAMES E. NEAL, citizens of the United States, residing at Clarksville, in the county of Butler and State of Iowa, have invented and produced a new and original Design for Bed-Slat Supports, of which the following is a specification.

Our invention relates to a new and novel design for a support for the slats or bed-bottoms of a bed; and the leading feature consists in the novel configuration given to the support, whereby it may be readily distinguished from other devices now in common use for the same purpose.

The accompanying drawing represents a perspective view of a bed-slat support constructed according to our design.

In the said drawing the reference-numeral 1 designates the support, comprising the lower horizontal portion 2 and the vertical sides 3. These sides, at their upper ends, are formed with laterally-extending enlargements 3^a,

formed with prongs 4 at the upper ends and with screw-holes 5 intermediate the ends. 25

In practice the supports are secured to the side rails of a bedstead at suitable distances apart and secured thereto by means of the prongs and screws passing through the screw-holes. The ends of the slats are then engaged 30 with the horizontal portions of the support, whereby they are supported or held in a horizontal position.

Having thus described our invention, what we claim is—

The design for a bed-slat support, substantially as herein shown and described.

In testimony whereof we have hereunto set our hands in presence of two subscribing witnesses.

WILLIAM MORRISON.
JAMES E. NEAL.
